DESIGN FOR A CASING FOR A FLOOR POLISHING MACHINE OR THE LIKE

Andrew L. Henkel and Burke M. Ewing, Chicago,
Ill., assignors to The Brunswick - Balke-
Collender Company, Chicago, Ill., a corpora-
tion of Delaware

Application November 25, 1940, Serial No. 96,779

Term of patent 14 years

To all whom it may concern:

Be it known that we, Andrew L. Henkel and Burke M. Ewing, both citizens of the United States, both residing in the city of Chicago, in the county of Cook, State of Illinois, have invented a new, original and ornamental Design for a Casing for a Floor Polishing Machine, or the Like, of which the following is a specification, reference being had to the accompanying drawing, forming a part thereof.

Figure 1 is a perspective view on a reduced scale

of a casing for a floor polishing machine or the like, showing our new design;

Figure 2 is a top plan view;

Figure 3 is a side elevational view; and

Figure 4 is a front elevational view thereof.

We claim—

The ornamental design for a casing for a floor polishing machine or the like, as shown.

ANDREW L. HENKEL.
